UNITED STATES PATENT OFFICE.

LEWIS A. MAPEL, OF ST. LOUIS, MISSOURI, ASSIGNOR TO AUTOMATIC APPLIANCE COMPANY, OF ST. LOUIS, MISSOURI, A CORPORATION OF MISSOURI.

DRAIN VALVE.

Application filed November 6, 1919. Serial No. 336,195.

To all whom it may concern:

Be it known that I, LEWIS A. MAPEL, a citizen of the United States, residing at the city of St. Louis and State of Missouri, have 5 invented a new and useful Drain Valve, of which the following is a specification.

This invention relates to drain valves.

An object of the invention is to provide a 10 novel and improved drain valve specially designed for use in connection with laundry equipment though not exclusively restricted to such use.

Another object of the invention is to provide an improved drain valve having combined therewith novel and efficient mechanism for holding the valve in closed position and capable of operation to permit the valve to open.

An additional object of the invention is 20 to provide an improved drain valve combined with a device for closing the valve capable of manual or automatic operation to permit the valve to open.

Another object of the invention is to provide an improved drain valve combined with 25 novel controlling mechanism for holding the valve closed and capable of operation to permit the valve to open as desired.

There are various other objects which I 30 desire to accomplish by the improvements embodied in the invention and which do not require specific mention, as the objects and means by which they are accomplished will be made obvious by the following description in which reference is made to the drawings, and in which:

Fig. 1 is an elevation of a drain valve mechanism embodying the invention.

Fig. 2 is another elevation of the device 40 having the gage tube mounted in a different position from that shown in Fig. 1.

Fig. 3 is an enlarged sectional view illustrating important features of the invention.

Fig. 4 is a view illustrating parts of the 45 electric circuit wire connections.

As shown, the present invention is in connection with a controlling mechanism and an electric relay mechanism, enclosed within the housing A. One form of controlling mechanism is disclosed in my prior Patent No. 1,265,933, dated May 14, 1918, and another form of controlling mechanism is disclosed in a co-pending application filed May 5, 1919, Serial No. 294,957; and the relay 55 mechanism is disclosed in a co-pending ap-

plication filed July 13, 1918, Serial No. 244,753. Neither of said mechanisms is claimed herein, for which reason the details thereof are not illustrated in the drawings, nor specifically set forth in the description. 60

For present purposes, it is only necessary to understand that the mechanism herein shown and described is arranged to operate as hereinafter set forth.

The water from the laundry tub (not 65 shown) is admitted into a chamber 1 through a passage 2. The chamber 1 is provided with a discharge opening or outlet through which the water is discharged at the proper time, and said opening or outlet is controlled 70 by a valve. As shown, the discharge opening or outlet is provided with a valve seat 3 to and from which the valve is movable to close and to open the outlet. The valve and the controlling mechanism for the valve are 75 of novel construction and mode of operation and constitute important features of the invention. The valve comprises a sleeve 4 having a circumferential flange 5. The sleeve 4 below the flange 5 is exteriorly 80 threaded and supports a disc 7 which carries and presses a gasket 6 against the valve seat 3 to close the outlet passage. The disc 7 fits on the threaded end of the sleeve 4 and may be provided with projections 8 85 which may be engaged to hold the disc in position while assembling the valve.

A rod 9 extends through an opening in the upper end of the sleeve 4 and is capable of limited axial movement. A collar or 90 flange 10 on the rod limits movement of the rod in one direction. A spring 11 encircles the rod 9 within the sleeve 4, the upper end of the spring bearing against the end wall of the sleeve 4 and the lower end of the 95 spring bearing against a nut 12 screwed onto the lower end of the rod. It is obvious that the upward movement of the rod will cause the spring 11 to press the valve to closed position, and that any additional 100 movement of the rod after the valve has been closed serves to compress and tension the spring. The upper end of the rod 9 is connected with an actuating device by a flexible connection 13 which may be, and 105 preferably is, in the form of a chain, though I do not limit myself in this particular as other forms of flexible connections may be employed. The device for operating the connections to the valve comprises a lever 110

14 having a bifurcated portion 15 supported on the pivots 16, an arm 17 extends from each branch 15 of the lever and the upper end of the connection 13 is secured to a connection 18 extending between the arms 17. When the lever 14 is in its lower position as indicated by dotted lines in Figs. 2 and 3, the valve connections are lowered and the valve is permitted to open.

10 In its lower position, the lever bears against a bumper 19 yieldingly supported by a spring 20 and a support 21. The bumper 19 being yieldingly supported relieves the shock when the lever 14 is thrown down from its upper adjustment to its lower position to enable the valve to open. In the lower position of the lever, the flexible connection 13 bends between the flanges of a rotary guide member 22.

20 The movement of the lever 14 to position to close the valve causes the spring 11 to be compressed and tensioned, so that the valve is held pressed against the valve seat by the power of the spring. When the lever is in position to hold the valve closed, as shown in Fig. 3, the connection 18 is out of axial alignment with the rod 9 and the pivot 16, so as to provide a toggle connection whereby the power of the spring 11 as well as the 25 weight of the valve and the valve connections are exerted to hold the lever 14 in its raised position. An adjustable abutment 23 is provided for the lever 14 so that the position in which said lever will be stopped may 30 be accurately regulated to insure that the valve will be securely held closed and at the same time be readily opened.

To prevent leakage through the valve a cup 24 is provided in connection with the 40 sleeve 4, said cup being screwed onto the sleeve and preventing the leakage of water through the valve around the rod 9.

In order to indicate the depth of the water in the tub or other receptacle with which 45 the device is used, a gage tube 25 may be provided. The gage tube is shown at one side of the device in Fig. 1 and at another side of the device in Fig. 2, it being obvious that the gage may be located wherever desired. The gage opens into the valve chamber 1. A partition 26 is within the valve chamber and has a hole therethrough to permit movement of the rod 9 and to permit slow passage of the water from the valve 55 chamber into the gage tube. The partition restricts the flow of the water and prevents the water from flowing too rapidly into the gage tube and into the pipe 27 to which the valve connections operate.

60 The mechanism set forth in the preceding description comprises a manipulative valve mechanism, since the lever 14 may be moved by hand as required to open and to close the valve. On some occasions it is desirable 65 to trip the lever 14 automatically in order

to permit the valve to open under a predetermined interval of time, or, under predetermined conditions. I have provided mechanism for effecting such automatic operation of the lever 14. The mechanism for this purpose, as shown, comprises an armature plunger 28 movable by an electromagnet 29 in a direction to move the lever 14 a distance sufficient to trip the toggle connection and permit the valve to open. The 75 armature plunger 28 at its upper end supports a screw 30 extending through a hole in one arm of a switch member 31. The switch member 31 is supported on a pivot 32 and has a contact member 33 at one end thereof movable into and out of contact with another contact member 34 as required to open and to close the circuit to the electromagnet. A spring 35 is supported between the switch member 32 and the plunger 28. 85

A wire 36 leads from the contact member 33 to the magnet and the other wire 37 leads to the magnet from a connection 38.

A switch device B of any usual or known construction may be used to open and to 90 close the circuit to the electromagnet in any usual or known manner. As the switch is a well known commercial article and as the details thereof constitute no part of the present invention, the construction of the 95 switch is not shown, it being well understood that operation of an electric switch to one adjustment closes an electric circuit, and operation of the switch to another adjustment opens the electric circuit. This 100 well known fact makes wholly unnecessary specific illustration of a well known commercial switch.

It is known that the controlling mechanism A is settable for operation to close an 105 electric circuit comprising the wires 38 after any predetermined interval of time. The construction of the controlling mechanism is claimed in my said prior Patent No. 1, 265,933, of May 14, 1918, and in my said application Serial No. 294,957, filed May 5, 110 1919, and is not claimed herein, it being sufficient for present purposes to know that the circuit through the wires 39 may be closed after any predetermined interval of time. 115 Therefore, if the switch B be closed it is obvious that after a desired interval of time the circuit will also be closed by operation of the controlling device A. When the circuit is completely closed by operation of the 120 controlling mechanism A (it being understood that the switch B is set in closed position) the magnet 29 is energized with the result that the armature plunger 28 is actuated outwardly a distance sufficient to force 125 the lever 14 away from its position shown in Fig. 3. Such movement of the lever 14 is sufficient to carry the connection 18 to the left in Fig. 3 far enough to permit the valve to open, the lever moving by the weight of 130

the parts and under the impulse of the spring 11 to the position shown in dotted lines. The movement of the armature plunger 28 opens the circuit to the magnet by 5 moving the contact member 33 out of contact with the member 34, thus de-energizing the magnet, which is desirable as the energy of the magnet is no longer needed.

Subsequent closing of the valve by movement of the lever 14 to its upper position 10 restores the contact member 33 into contact with the member 34 ready for another operation.

What is claimed is:

15 1. In a device of the character described, comprising a chamber having an outlet passage, a valve at the effluent end of said passage for opening and closing the same and being movable to open position by gravity and the pressure of the water in the chamber, a lever pivoted in approximate alignment with the axis of said valve, an arm on 20 said lever which is wholly on one side of said pivot in one position of the lever and which extends to the other side of the pivot in another position of the lever, a spring bearing 25 against said valve, and a connection from said spring to said arm whereby movement of said lever to said other position will move the valve to hold the same in closed position.

2. In a device of the character described, comprising a chamber having an outlet passage, a valve at the effluent end of the passage for opening and closing the same and being movable to open position by gravity and the pressure of the water in the chamber, a lever pivoted in approximate alignment with the axis of said valve, an arm on 35 said lever which is wholly on one side of said pivot in one position of the lever and which extends to the other side of the pivot in another position of the lever, a spring bearing 40 against said valve, a connection from said spring to said arm whereby movement of said lever to said other position will move the valve to hold the same in closed position, and an abutment for engaging and supporting the lever in position to hold the valve closed.

3. A device of the character described, comprising a chamber having an outlet passage, a valve at the effluent end of said passage for opening and closing the same and being movable to open position by gravity and the pressure of the water in the chamber, a spring for pressing said valve to 45 closed position, a lever, a device connecting said lever and said spring and having its point of connection with the lever movable across the line of the axis of the valve when 50 the lever is moved in a direction away from the valve to place said spring under tension, and means for supporting the lever in position to retain the spring under tension.

4. A device of the character described,

comprising a chamber having an outlet passage, a valve at the effluent end of said passage for opening and closing the same and being movable to open position by gravity and the pressure of the water in the chamber, a spring for pressing said valve to closed position, a lever, a device connecting said lever and said spring and having its point of connection with the lever movable across the line of the axis of the valve when 70 the lever is moved in a direction away from the valve to place said spring under tension, means for supporting the lever in position to retain the spring under tension, and mechanism for moving said lever from said 80 position to enable said valve to open.

5. A device of the character described, comprising a chamber having an outlet passage, a valve at the effluent end of said passage for opening and closing the same and being movable to open position by gravity and the pressure of the water in the chamber, a spring for holding said valve in closed position, a device for tensioning said spring as required to hold said valve in closed 85 position, a lever for operating said device as required to close said valve and to place said spring under tension, a connection between said lever and said device which is on one side of the line of the axis of said valve 90 when the valve is open and which is on the other side of said line when the valve is closed, means for moving said lever in a direction to permit said valve to open, and an element for supporting said connection when 95 said lever is in position to permit the valve to open.

6. A device of the character described, comprising a chamber having an outlet passage, a valve at the effluent end of said passage for opening and closing the same and being movable to open position by gravity and the pressure of the water in the chamber, a spring for holding said valve in closed position, a device for tensioning said spring 100 as required to hold said valve in closed position, a lever for operating said device as required to close said valve and to place said spring under tension, a connection between said lever and said device which is on one side of the line of the axis of said valve 105 when the valve is open and which is on the other side of said line when the valve is closed, an adjustable support for supporting the lever in position to hold the valve closed, 110 means for moving said lever in a direction to permit said valve to open, and an element for supporting said connection when said lever is in position to permit the valve to open.

7. A device of the character described comprising a chamber having an outlet passage, a valve for closing and opening said passage, a rod extending through said valve, a spring encircling said rod for pressing 120 130

said valve to closed position, a lever, a flexible connection between said lever and said rod whereby said lever when in one position will hold the valve closed, an electro-magnet 5 and an armature device actuated by the electro-magnet for moving said lever to position to permit the valve to open.

8. A device of the character described comprising a chamber having an outlet passage, a valve for closing and opening said passage, a rod extending through said valve, a spring encircling said rod for pressing said valve to closed position, a lever, a flexible connection between said lever and said 15 rod whereby said lever, when in one position, will hold the valve closed, an electro-magnet, an armature device actuated by the electro-magnet for moving said lever to position to permit the valve to open, and means 20 for causing the electro-magnet to become de-energized as an incident to movement of said device.

9. A device of the character described, comprising a chamber arranged to receive 25 water and having an outlet passage, a valve for opening and closing said passage and being movable to open position by the pressure of the water in said chamber, a sleeve on said valve, a spring enclosed within said 30 sleeve, a lever, a flexible connection from said spring to said lever whereby movement of the lever to one position will compress said spring and close the valve, a stationary element for holding said lever in said position, and an electric device for imparting initial movement to said lever from said position to permit said valve to be opened by the pressure of the water in said chamber.

10. A device of the character described, 40 comprising a chamber arranged to contain water and having an outlet passage, a valve for opening and closing said passage and being movable to open position by the pressure of the water in said chamber, a sleeve on said valve, a rod extending through said sleeve, a spring encircling said rod in said sleeve, an enclosure for said sleeve supported by said valve, a lever, a flexible element having one end connected to said rod 45 and the opposite end connected to said lever, means for supporting said lever in position to cause said connection and said rod and said spring to hold the valve in closed position, a support, and an actuator mounted 50 in said support for imparting initial movement to said lever from said position to permit the pressure of the water in said chamber to move the valve to open position.

60 11. A device of the character described, comprising a chamber arranged to contain water and having an outlet passage, a sleeve

at the effluent end of said passage for opening and closing the same and being movable to open position by the pressure of the 65 water in said chamber, a lever, a connection from said valve to said lever whereby movement of the lever to one position will close the valve and slight movement of said lever from said position will permit pressure of 70 the water to open the valve, means for supporting said lever in the position in which the valve is closed, a support, and an actuator in said support for imparting movement of said lever from said position to permit the pressure of the water to open said valve.

12. A device of the character described comprising a chamber having an outlet passage, a partition in said chamber having a 80 hole therethrough, a gage communicating with said chamber on the opposite side of said partition from said outlet passage, a valve for opening and closing said passage, a rod in connection with said valve extending through said hole in said partition and leaving space for passage of water through said hole in any position of said rod, and means for actuating said rod to close said valve.

13. A device of the character described comprising a chamber having an outlet passage, a partition in said chamber having a hole therethrough, a gage communicating with said chamber on the opposite side of 95 said partition from said outlet passage, a valve for opening and closing said passage, a rod in connection with said valve extending through said hole in said partition and leaving space for passage of water through 100 said hole in any position of said rod, a lever, and a connection between said rod and said lever whereby movement of said lever to one position will actuate said rod to close said valve.

14. A device of the character described comprising a chamber having an outlet passage, a partition in said chamber having a hole therethrough, a gage communicating with said chamber on the opposite side of 110 said partition from said outlet passage, a valve for opening and closing said passage, a rod in connection with said valve extending through said hole in said partition and leaving space for passage of water through 115 said hole in any position of said rod, a lever, a connection between said rod and said lever whereby movement of said lever to one position will actuate said rod to close said valve, means for holding said lever in position to hold the valve closed, and means for moving said lever from said position.

LEWIS A. MAPEL.
